(57) **CLAIM**

The ornamental design for a mobile phone protective case, as shown and described.

DESCRIPTION

FIG. 1 is a front, left-side, and bottom perspective view of a mobile phone protective case showing the case component in isolation without the detachable back panel component for clarity of disclosure.

FIG. 2 is a rear, right-side, and top perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a front, left-side, and bottom perspective view of the mobile phone protective case showing the detachable back panel component in isolation for clarity of disclosure.

FIG. 10 is a rear, right-side, and top perspective view thereof.

FIG. 11 is a front view thereof.

FIG. 12 is a rear view thereof.

FIG. 13 is a left side view thereof.

FIG. 14 is a right side view thereof.

FIG. 15 is a top view thereof.

FIG. 16 is a bottom view thereof.

FIG. 17 is an exploded front, left-side, and bottom perspective view of the mobile phone protective case showing the case component and the detachable back panel component separated for clarity of disclosure.

FIG. 18 is a front, left-side, and bottom perspective view of the mobile phone protective case showing my new design with the case component and the detachable back panel component in the assembled state.

FIG. 19 is a rear perspective view thereof.

FIG. 20 is a front view thereof.

FIG. 21 is a rear view thereof.

FIG. 22 is a left view thereof.

FIG. 23 is a right view thereof.

FIG. 24 is a top view thereof; and,

FIG. 25 is a bottom view thereof.

For clarity of disclosure, the separable components of the mobile phone protective case are shown in isolation in FIGS. 1-16 and separated in FIG. 17. Although the mobile phone protective case, in which the claimed design is embodied, consists of a case component and a detachable back panel component, the claim is directed to the overall ornamental appearance of the mobile phone protective case in its entirety and does not extend to the ornamental appearance of either of the individual components in isolation.

The broken lines in the drawings depict portions of the mobile phone protective case that form no part of the claimed design.
